UNITED STATES PATENT OFFICE.

JOSEPH SPEAR MAXWELL, OF CUMBERLAND, MARYLAND.

COKE-OVEN.

SPECIFICATION forming part of Letters Patent No. 761,521, dated May 31, 1904.

Application filed February 17, 1904. Serial No. 193,950. (No model.)

To all whom it may concern:

Be it known that I, JOSEPH SPEAR MAXWELL, a citizen of the United States, and a resident of Cumberland, in the county of Allegany and State of Maryland, have invented new and useful Improvements in Coke-Ovens, of which the following is a full, clear, and exact description.

This invention relates to improvements in coke-ovens; and the object is to provide an oven having more grate capacity than the usual round or "beehive" ovens occupying practically the same space.

A further object is to so construct the oven that repairs may be made at small expense.

Other objects of the invention will appear in the general description.

I will now describe a coke-oven embodying my invention and then point out the novel features in the appended claims.

Reference is to be had to the accompanying drawings, forming a part of this specification, in which similar characters of reference indicate corresponding parts in all the figures.

Figure 1 is an elevation, partly in section, of a series of coke-ovens embodying my invention. Fig. 2 is a plan thereof, partly in section; and Fig. 3 is an elevation, partly in section, showing the end oven and intermediate ovens.

Arranged at each end of a long series of ovens formed in a single structure 1 are two ovens 2 3. These ovens 2 3 are separated by a partition-wall 4 and comprise end walls 5, the front wall 6, and the rear wall 7. These walls and partition form ovens rectangular in cross - area—that is, the several walls are straight vertically and lengthwise; but for the purpose of additional strength the front wall 4 is inclined inward from the base to the roof. Each oven is provided with an arched roof 8, provided at its center with a vent 9. It will be noted that the oven is formed in a rectangular brick or plate, as I find such shape more convenient in brickwork. It will also be noted that the roofs 8 are arched or curved from the partition 4 to the end walls and that transversely the said roofs are on straight lines. By this construction the capacity of each oven 50 is greatly increased over an oven having sub-

stantially round or curved walls and a cupola top and not occupying a greater ground space.

The front wall of each oven is provided with two openings 10, through which the coke may be drawn, and each opening is closed by a brick wall when the oven is in operation, as indicated at 11. Spaced from the outer sides of the end walls 5 are vertical beams 12, which are seated firmly in the ground and as here shown consist of I-beams, although they may be otherwise shaped. Secured to the outer sides of the end walls and also secured to the beams 12 are transverse beams 13, and the upper ends of the beams 12 are connected by tie-rods 14, which are here shown as provided with turnbuckles 15 for the purpose of tightening the same. The inner end walls 5 of the pair of end ovens are connected by short beams 16 with an I-beam 17, attached to the adjacent end of the structure 1. By means of these several beams and the tie-rods it is obvious that the end walls 5 are firmly braced against downward pressure caused by the arched roofs, and it may be here observed that there may be practically little or no pressure exerted on the front wall. As the structure 1 containing the long series of ovens is braced from the end ovens, tie-rods are not required over the intermediate ovens. Filling the spaces between the vertical beams 12 and the end walls 5 and supporting the transverse beams are brick pilasters 12^a, which obviously will add materially to the strength of the oven.

Over the arched roofs is a packing 18, of dirt or other suitable material, which provides a level or flat top surface upon which track-rails 19 are supported. These tracks 19 are secured to cross-ties 20, and the tracks or rails are arranged above the plane of the tie-rods 14, so that said tie-rods will not interfere with movements of the coal-carrying cars movable on the rails. The track is arranged at one side of the longitudinal center of the structure—that is, at one side of the vents 9—so that coal may be discharged from the cars through said vents into the ovens.

The most important improvement in my coke-oven construction, it will be understood, is the straight arch, as by such arch repairs 100

on the arch are saved, as it is practically indestructible, whereas in the beehive oven the arch is constantly falling down, not, however, from wear, but because there is nothing 5 to restrain the globular arch on the side where the doors are formed. Further, in a square oven as many doors as are desirable can be built in the front wall, so as to facilitate the drawing of the coke from the oven. In the 10 beehive oven there can only be one door.

Having thus described my invention, I claim as new and desire to secure by Letters Patent—

- 15 1. The combination with a series of coke-ovens, of a pair of coke-ovens arranged at each end of said series of ovens, arched roofs for the ovens, the curve of the arch being lengthwise of the oven, brace-beams arranged vertically outside of the end walls of each 20 pair of the end ovens, a pair of transverse beams connecting the end walls to the vertical beams, tie-rods connecting opposite vertical beams, and beam connections between the inner end wall of a pair and the adjacent end wall of the series of ovens.
- 25 2. The combination with a long series of coke-ovens, of a pair of coke-ovens arranged at each end of said long series of ovens, the ovens of each pair having straight end walls and straight front and rear walls, arched roofs 30 for the ovens, the curve of the arch being lengthwise of the ovens, brace-beams arranged vertically outside of the end walls of each pair of ovens, a pair of transverse beams connecting the end walls to the vertical beams, 35 tie-rods connecting opposite vertical beams, beam connections between the inner end wall

of the pair and the adjacent end walls of the long series of ovens, and tracks extended lengthwise over all of the ovens, said tracks being supported above the plane of the tie-rods over the end ovens, the tops of the arched roofs being provided with vents. 40

3. The combination with a long series of coke-ovens arranged in a single structure, of pairs of end ovens spaced from the structure, 45 each oven being rectangular in cross-area and having an arched top provided with a central vent, brace-beams extended upward along the end walls of the pair of ovens, tie-rods connecting opposite beams above the ovens, braces 50 extended across the spaces between adjacent walls and connecting said walls, a packing of dirt or the like supported on the ovens, and car-tracks extended along over all of the ovens at one side of the vents. 55

4. The combination with a plurality of coke-ovens arranged in a single structure, of a pair of ovens arranged at each end of the structure and spaced therefrom, brace-beams extended 60 across the spaces and connecting adjacent end walls, each of the ovens having two discharge-openings, closures for said openings, arched roofs for the ovens and having vents at the center, and car-tracks extended along over all of the ovens at one side of the vents. 65

In testimony whereof I have signed my name to this specification in the presence of two subscribing witnesses.

JOSEPH SPEAR MAXWELL.
